UNITED STATES PATENT OFFICE.

CLARENCE FANCHER, OF HUDSON FALLS, NEW YORK.

PAPER-PULP SCREEN.

Application filed July 16, 1925. Serial No. 44,052.

To all whom it may concern:

Be it known that I, CLARENCE FANCHER, a citizen of the United States of America, residing at Hudson Falls, in the county of Washington and State of New York, have invented certain new and useful Improvements in Paper-Pulp Screens, of which the following is a specification.

My invention relates to improvements in paper pulp screens and more particularly to means for operating the diaphragms thereof.

An important object of my invention is the provision of a device of this character in which a roller shoe takes the place of the usual fixed wooden shoe on the vertically movable plunger which engages the cam shaft.

Another object of my invention is to provide a device of the above mentioned character with a roller which is so related to the operating cam that the wear upon the roller shoe will be evenly distributed over its entire periphery thereby insuring the longest possible wear for the roller shoe, doing away with the necessity for frequently changing the shoe.

A further object of my invention is to provide means for changing the length of vibration of the diaphragm without replacing the cams.

Other objects and advantages of my invention will be apparent during the course of the following description.

In the accompanying drawings which form a part of this specification and wherein like characters of reference denote like or corresponding parts throughout the same,

Figure 1 is a side elevation of a portion of a machine embodying my invention, parts being broken away,

Figure 2 is an edge view thereof parts being broken away, parts in section, and parts being in elevation,

Figure 3 is a side elevation of one of the operating cams,

Figure 4 is an end elevation of the same,

Figure 5 is a side elevation of a portion of a machine embodying a modification of my invention, parts being broken away,

Figure 6 is an edge view thereof, parts being broken away, parts in section, and parts being in elevation, and

Figure 7 is a detail view showing the arrangement of the leaf springs.

In the drawings wherein for the purpose

of illustration is shown a preferred embodiment of my invention, the numeral 10 designates the customary vat of a pulp screen provided with the usual screen plates 11 and diaphragm 12. The vat 10 is mounted on standards 13 which in turn support and are supported by the customary longitudinal bridgertree 14 which supports journals for cam shaft 15 provided with the usual wells or recesses for lubrication of the cams 16, 65 said cams being spaced on shaft to correspond to the several compartments of the screen, and the shaft is rotated by means of a suitable pulley 17, or the like.

The cams are provided with a number of rises or swellings 18 spaced at equal distances apart and joined by convex surfaces forming gentle rises of outward curvature in contradistinction to intermediate hollows or recesses. These cams each comprise complementary sections having collars 19 at each end which are clamped together by bolts 20 which serve to clamp the cams to the shaft 15 to which they are also keyed. The cams are arranged in series, here shown as 70 three, of different sizes, for a purpose to be hereinafter described.

Roller hangers 21 are secured to diaphragm boards 22 and comprise forked or bifurcated lower ends 23 which support 85 bearings 24 in which the trunnions 25 of roller shoes 26 are journalled. The forked ends 23 are hollowed for the reception of lubricant for the bearings, and fit within casing sections 27 which are slotted at 28 90 for the roller shoe and spread out to cover the cams and are secured to the bridgertree 14 at their base. A transverse cross bar 29 is an extension part on each casing section and extends between the forks of the lower end of the hangers where they are bolted together and clamp and support a vertically and upwardly extending rod 30 which has its upper end threaded to receive the nut and cap 31 which bear against the coil spring 32 which in turn bears down on the hanger. It will be seen that upward movement of the roller shoe and hanger is resisted by the spring 32 which will return the shoe to its 95 normal position, and the tension of which may be adjusted by the nut.

The roller shoe rests upon the cam and is caused to reciprocate thereby. The different cam sizes are for the purpose of giving a larger or smaller pulsation to the diaphragm 100 105 110

- and may be changed by loosening the collars 19 and shifting them on the shaft, or the shaft may be moved longitudinally to bring a different sized cam under the roller shoe.
- 5 In the modification shown in Figures 5, 6, and 7, the cross bar 29 is dispensed with and a horizontally extending shelf member 33 is secured to the hangers, preferably formed integrally therewith. A channel bar 10 34 extends the full length of screen and is supported by the standards 13.
- A leaf spring 35 is bolted to the channel bar and extends over said shelf portion and is secured thereto by means of the clamp 36.
- 15 A bolt 37 is secured at one end to the bridge-tree and extends vertically through the shelf, spring and clamp and a substantial distance thereabove. A coil spring 38 surrounds the upper end of the bolt and is held in place 20 by the collar 39 which is adjustably secured in place by the nut 40.
- It will be seen that in this modification, upward movement of the hanger is resisted by both of the springs.
- 25 The shoe will rise and fall uniformly due to the fact that swellings 18 are connected by convex rather than concave or hollow surfaces, and as the cam is operating against a revolving surface the rise may safely be 30 more abrupt than is used with the sliding wood shoe block causing a sharper upward movement thereby keeping the plates more open and very much increasing their capacity and the output of the screen. As each 35 rise 18 of the cam comes in contact with the periphery of the roller shoe, the rising action of the swelling 18 upon the cam surface is in the nature of a blow, modified, it is true, by the gradual character of the curve forming 40 the adjacent swellings but nevertheless sufficient to exert a wearing effect upon the surface, which wearing effect, if repeated in the same place, would ultimately result in changing regularity of the cylindrical periphery of the surface of the roller shoe and 45 would form a succession of ridges. The resulting effect would be, moreover, to impart an irregular motion of constantly increasing disadvantage to the reciprocating diaphragm, instead of the uniform and wave-like undulations desirable in practice and 50 which insure the long life of the diaphragm and the maintenance of its efficient action upon the body of the pulp contained in the screen. This irregularity of the action of 55 the diaphragm is accompanied with sagging and irregular flexure thereof, with a consequent liability of rupture of the rubber along the inner edges of the wooden tank or vat, and is a difficulty which is met with in 60 ordinary practice wherein a constant wearing of the usual fixed wooden shoe has for its consequence a constant increasing pull on the diaphragm with a resulting rupture 65 which would not occur with the roller shoe.

By the expedient of proportioning the length of the periphery of the roller shoe to that of the cooperating cam, in such manner that the roller shoe has a much longer periphery than the cam and incommensurable therewith, the wearing action of the rises 18 is distributed evenly over the entire periphery of the shoe in the sense that, as the shoe revolves the rises of the cam do not strike portions of the periphery of the shoe which were struck by the cam rises of the revolution immediately preceding, but, on the contrary, portions of the surface of the roller shoe immediately in advance or in the rear thereof, thereby causing a progressive distribution about the entire periphery and maintaining a more constant position of the rubber diaphragm and prolonging its life.

The roller shoe should be considerably larger than the cam, and not in multiples thereof. I have found in practice that a ratio of 14 to 6 is very suitable, although other proportions may be used with equal success. The wear upon the shoe will be uniform, and the shaft, under these circumstances may be rotated in either direction, which is not the case with a fixed wooden plunger.

I prefer to make the roller shoe of metal and preferably of steel as it admits of lighter construction and less power to run, the cam is case hardened, and ground true. Due to slightness of wear, an even vibration of diaphragm is insured, which greatly lengthens its life and efficiency, and due to the fact that the shoe is a roller and spring pressed, its operation is practically noiseless, which is a great improvement over the old type of screens which caused a terrific din, especially when the iron shoe block is used to avoid down pull on the diaphragm.

A two year trial run under actual working strain gave a $\frac{1}{2}$ " drop to the diaphragm in place of the numerous $\frac{1}{2}$ " drops when the wood shoe block was used, and the surface of the roller shoe and cam was smoother than when first put in place.

While I have shown and described the preferred embodiment of my invention, it is to be understood that various changes in the size, shape, and arrangement of parts may be resorted to without departing from the spirit of my invention or the scope of the subjoined claims.

Having described my invention what I claim and desire to protect by Letters Patent is:

1. A paper pulp screen having a flexible diaphragm, a hanger connected to the diaphragm, a shoe attached to said hanger, a cam shaft, a series of rotary cams of different sizes, arranged on said shaft, said shoe being adapted to cooperate with one of said cams, and means whereby the cams may be

moved so that a different cam will cooperate with the shoe to impart a change of vibration to the diaphragm.

2. A paper pulp screen having a flexible diaphragm, a hanger connected to the diaphragm, an axially rotatory circular shoe journaled in said hanger, a cam shaft, a series of cams of different sizes arranged on said shaft, one of said cams being adapted to cooperate with said roller shoe to vibrate the diaphragm and means to shift the cams with respect to the roller shoe whereby a different cam may be made to engage the shoe to impart a different length of vibration to the diaphragm.

3. A paper pulp screen having a flexible diaphragm, a hanger connected to said diaphragm, an axially rotatory circular shoe journaled in said hanger, a cam shaft, a series of cams of different sizes arranged on said shaft, one of said cams being adapted to engage the said roller shoe to vibrate the diaphragm, the length of the periphery of the shoe being greater than that of the cams and practically incommensurable therewith, and means whereby the cams may be shifted with respect to the roller shoe in order that a different cam may engage the shoe to change the length of vibration of the diaphragm.

4. A paper pulp screen having a flexible diaphragm, a hanger connected to said diaphragm, said hanger having its lower end forked, bearings carried by the forked end, a roller shoe having trunnions journaled in the bearings, the forks being hollowed out to form chambers leading to the bearings for lubrication of said bearings, a cam shaft, a cam on said shaft, said cam having gentle rises of outwardly curved surfaces cooperat-

ing with the shoe, the length of the periphery of the shoe being greater than that of the cam and practically incommensurable therewith.

5. A paper pulp screen having a flexible diaphragm, a hanger connected with said diaphragm, said hanger having its lower end forked, bearings carried by the forked end of the hanger, a roller shoe having trunnions journaled in said bearings, the forks being hollowed out to form lubricant chambers leading to the bearings, a spring adapted to resist upward movement of the hanger, a cam shaft, a cam block on said shaft comprising a series of cams, said cams having gentle rises of outwardly curved surfaces adapted to cooperate with the roller shoe, the length of the periphery of the roller shoe, being greater than that of the cams and practically incommensurable therewith, and means whereby the cam block may be shifted to bring different cams into engagement with the roller shoe to change the length of vibration of the diaphragm.

6. A paper pulp screen having a flexible diaphragm, a hanger connected to said diaphragm, said hanger having its lower end forked, bearings carried by the forked end of the hanger, a roller shoe having trunnions journaled in said bearings, the forks being hollowed out to form lubricant chambers leading to the bearings, a split casing section surrounding the hanger and roller shoe, a rod passing upwardly through a portion of the hanger, a spring secured to said rod and pressing down on the hanger, a cam shaft, and a cam mounted thereon and adapted to engage the roller shoe.

In testimony whereof I affix my signature.
CLARENCE FANCHER.
